UNITED STATES PATENT OFFICE.

LUCEAN B. STANLEY, OF CLEVELAND, OHIO.

FENDER.

1,182,047.

Specification of Letters Patent.

Patented May 9, 1916.

Application filed September 28, 1914. Serial No. 863,921.

To all whom it may concern:

Be it known that I, LUCEAN B. STANLEY, a citizen of the United States, residing at Cleveland, in the county of Cuyahoga and State of Ohio, have invented certain new and useful Improvements in Fenders, of which the following is a specification.

My invention relates to fenders for railway cars, and as its primary object contemplated an individual fender for each wheel, the fenders being movable into and out of engagement with the railway rails.

As a further object, the invention resides in the provision of simple and efficient means for simultaneously actuating the two fenders should occasion demand.

The invention further aims to provide a fender structure in which the fender blades or shoes are so positioned relatively to the wheels of the car as to engage the track or rail directly in advance thereof.

The above and additional objects are accomplished by such means as are illustrated in their preferred embodiment in the accompanying drawings, described in the following specification and then more particularly pointed out in the claim which is appended hereto and forms a part of this application.

In describing my invention in detail reference will be had to the accompanying drawings wherein like characters denote like or corresponding parts throughout the several views, and in which:

Figure 1 is a side elevation of a portion of a car illustrating the arrangement of one of the fender devices thereupon; Fig. 2 is a detail perspective view of one of the said devices; Fig. 3 is an enlarged elevation of one of the fender blades or shoes; and Fig. 4 is a detail perspective view of the operating means.

Referring now to the drawings by numerals, 1 designates, as an entirety, a railway car, 2 the railway rails, and 3 the wheels of the car, the latter having arranged slightly in advance thereof and in such adjacency to the rails 2 as to be moved into and out of engagement therewith, the blades or shoes 4 forming a part of the fender device.

Each shoe is supported by means of a supporting plate 5 secured as at 6 to the forward truck of the car 1 at a point slightly in advance of the front wheels 3. Plate 5 carries a pin 7 at its lower extremity, the

pin in turn supporting the plate or shoe 4 in the desired manner. The respective pins 7 act as a fulcrum for the respective shoes or plates.

A rod 8 is pivoted as at 9 to each shoe 4 at its rear end or extremity, the said rod fitting a bifurcation or recess 10 therefor. The opposite end of each rod 8 is pivoted, as at 11, to a second rod 12 fulcrumed intermediate its ends as at 13, the plate 5 supporting the pin 14 which acts as the fulcrum medium. The opposite end of rod 12 is fastened as at 15 to a transverse rod 16 arranged beneath the body of the car 1, the said rod 16 being actuatable to provide for simultaneous movement of the respective shoes or plates. Said rod 16 is bodily movable to actuate the respective rods 12 by means of a lever 17 fulcrumed equi-distant its ends as at 18 and fastened as at 19 at its opposite end to an operating rod 20. A bracket 21 is secured to the under side of the car body 1 to serve as a support means for the lever 17. The rod 20 is connected at its opposite end, that is, at a point remote from its connecting point 19, to an arm 21 fulcrumed intermediate its ends as at 22 and actuatable upon its fulcrum point by means of a rod 23 in turn connected to a link 24 directly engaging a crank device 25 positioned forwardly of the car 1 and in such adjacency to the control means therefor as to be operated by the motorman or engineer as the case may be.

Fender plates or shoes 4 are normally maintained out of engagement with the rails 2. Should occasion demand, the said fender shoes may be simultaneously moved into engagement with the respective rails through actuation of the crank arm 25, the latter being turnable to move the member 21, said member in turn being movable to actuate the lever 17. As shown to advantage in Fig. 2, lever 17 is movable or actuatable to provide for simultaneous movement of the fulcrum rods 12. Each rod 12 having associated therewith a connecting rod 8, and each rod 8 being affixed to one of the fender plates 4, it is apparent that the latter may be moved either into or out of engagement with the rails 2 so as to prevent passage of the wheels 3 over a person or an animal in the event of the car coming in contact therewith.

From the foregoing, taken in connection

with the accompanying drawings it will be noted that the rails 2 may be quickly and effectually cleared; that the two fender shoes or plates are simultaneously movable through actuation of a single operating element; and that the entire device may be operatively associated with a car or the like without modifying the structure of the latter to a material extent.

10 In reduction to practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as defined in the appended claim.

Having thus fully described my inven-

tion, what I claim as new and desire to 25 secure by Letters Patent, is:—

In a fender attachment for railway cars, a pair of fender plates positioned forwardly of the front wheels of the car, a support for each plate affixed to the car truck, a rod fulcrumed intermediate its ends, a rod extending transversely of the car and secured to the first mentioned rod, a fulcrumed rod secured to said support, the last mentioned rod having connection with the transverse 35 rod, a rod connecting each of the last mentioned fulcrumed rods with the fender plates, and means connected to the first mentioned fulcrum rod and actuatable to simultaneously move the fender plates either 40 into or out of engagement with the railway rails.

In testimony whereof I affix my signature in presence of two witnesses.

LUCEAN B. STANLEY.
